DEVICE FOR GRINDING AND POLISHING
CYLINDERS

Friedrich Kettlein, Britz, Germany

Application September 28, 1931, Serial No.
565,576, and in Germany October 1, 1930.
Renewed March 1, 1933

1 Claim. (Cl. 51—54)

The present invention relates to improvements in grinding machines for grinding and polishing cylinders, more particularly coppered or copper covered intaglio cylinders by means of a plain 5 horizontal grinding or polishing wheel respectively which is adapted to carry out an oscillating movement over an axis vertical to the work piece.

In contradistinction to known devices of the 10 aforementioned description, the present invention is performed without the provision of belts, chains or flexible shafts of any description. In combination with the preferred manner of performing the present invention provision is made 15 to allow for the grinding tool to be swung free from the work piece, while a known sliding weight lever is provided for the regulation of the grinding pressure, serving at the same time as rest for the swung up tool carrier.

20 Other details of the present invention and a simple and reliable device for driving the grinding wheel will become apparent in the course of the following description:—

In the accompanying drawing, forming part 25 of this specification and in which like numerals designate like parts throughout the preferred embodiment of the present invention is shown for the purpose of illustration:—

Fig. 1 is a schematic illustration of the tool 30 carrier movement.

Fig. 2 is a similar illustration, showing the rotary drive for the grinding wheel.

Fig. 3 shows the swing-device for the tool carrier.

35 Fig. 4 is a side of the complete device.

Fig. 5 is a plan of the complete device.

Fig. 1 shows the movement of the tool carrier from the side. 1 represents the cylinder to be ground in horizontal position, 2 is the tool carrier or grinding head which rotates on the vertical axis 3. The tool carrier is shown in the medium position, while the two extreme limits of movement are shown in dotted lines. This movement is caused by parts 4 and 5 constituting an elbow lever swinging around axis 6. The oscillating movement of this elbow lever is executed by means of a cam or eccentric disc 7 and roll 8. Fig. 2 shows the manner in which the aforementioned rotary movement of the 45 grinding wheel is effected. 9 is a continually rotating pinion in permanent engagement with gear wheel 10 which in its turn is attached to parts 4 and 5. Pinion 9 is driven by electro-motor 25 by means of reduction gears as clearly shown in Figs. 4 and 5. Gear wheel 10 drives the

grinding wheel 2 over a bevel gear 11 and 12, a shaft 13, a second set of bevel gears 14 and 15, a set of gear wheels 16 and 17, which latter is mounted on shaft 3 together with the grinding tool 2. Bevel gears 11, 12 and 14, 15, as well 60 as shaft 13 and gear wheels 16, 17 are mounted on the tool carrier or grinding arm and follow the latter's oscillating movement.

By transmitting the movement of pinion 9, the axis of which is fixed, to gear wheel 10, the axis 65 of which moves radially to axis 6 in a to and fro movement, the drive of grinding wheel 2 is subjected to a mechanically oscillating irregularity which has been proved to be an extremely favourable effect on the grinding and polishing 70 process.

Having now particularly described my present invention and the manner in which it is to be performed, I declare that what I claim is:—

A grinding device for grinding and polishing 75 cylinders, more particularly copper coated intaglio cylinders, comprising in a combination a lever which is pivoted around a fixed axis at a distance from one end, means arranged at one end of said lever, adapted to cause an oscillating 80 movement of said lever and a gear wheel provided at the other end of said oscillating lever, said gear wheel being in permanent engagement with a pinion rotating around said fixed axis, a tool carrier pivoted at one end on the support of 85 said gear wheel and carrying a horizontal grinding tool at the other end, driving means comprising bevel gear wheels to drive said grinding tool, said driving means being mounted on said tool carrier and driven from said gear wheel, the axis 90 of said gear wheel being adapted to swing radially around the fixed axis of said pinion in combination with the movement of said oscillating lever, causing the whole device to follow the 95 movement of said oscillating lever, said tool carrier being adapted to be swung free from the work piece by swinging it upwards around its articulation, means for the regulation of the grinding pressure acting on said tool carrier 100 and supporting it when swung up in to a position of rest.

FRIEDRICH KETTLEIN.
